UNITED STATES PATENT OFFICE.

HARRY J. HAGERLING, OF BELLEVILLE, ILLINOIS.

DESIGN FOR A BADGE.

No. 38,360.

Specification for Design.

Patented Dec. 18, 1906.

Application filed November 12, 1906. Serial No. 343,161. Term of patent 14 years.

To all whom it may concern:

Be it known that I, HARRY J. HAGERLING, a citizen of the United States, residing in Belleville, in the county of St. Clair and State of Illinois, have invented a new, original, and ornamental Design for Badges.

The accompanying drawing, which is a front elevation, illustrates my new, original, and ornamental design for badges.

I claim—

The ornamental design for a badge as shown.

HARRY J. HAGERLING.

In presence of—

NELLIE V. ALEXANDER,
BLANCHE HOGAN.
